PAPER DISPENSER

Frank L. Broeren, Menasha, Wis., assignor to
 Marathon Paper Mills Company, Rothschild,
 Wis., a corporation of Wisconsin

Application October 1, 1934, Serial No. 746,289

4 Claims. (Cl. 312—62)

The dispenser of the present invention is designed particularly for use in the dispensing of interleaved folded waxed sheets which by reason of their smooth surface must be firmly and evenly retained in stacked formation during the dispensing operations, since they do not tend to frictionally adhere to one another, but develop a tendency to slip or slide, which must be overcome in order to prevent displacement.

The mechanism of the present invention therefore makes provision for the confinement and retention of the stacked sheets during all stages in the dispensing operation, and also makes provision for progressively increasing the distance from the base of the stack to the point of application for the feeding pressure concurrently with the depletion of the stack, so that as the stack is depleted the feeding pressure will be applied at the proper point to most advantageously counteract any tendency toward displacement of the sheets until the last sheet has been withdrawn.

Further objects and details of the invention will appear from the description thereof in conjunction with the accompanying drawings, wherein,

Figure 1 is a perspective view of a dispenser embodying the features of the present invention; Fig. 2 is an enlarged vertical section taken on line 2 of Fig. 1;

Fig. 3 is a sectional view of the rear face of the follower plate taken on line 3 of Fig. 2;

Fig. 4 is a sectional elevation showing a modified form of follower plate; and

Fig. 5 is a sectional view on reduced scale taken on line 5 of Fig. 4.

The embodiment illustrated comprises a metal box or cabinet 10 having a cover 11 hinged to the upper edge of the rear wall 12 by means of a pintle 13. The pintle is located inside of the rear upper corner of the cabinet so that the rear wall 12 will present an even or uninterrupted surface for attachment to a wall or the like, or for close contact with a wall in cases where the cabinet is supported upon a table or counter adjacent to the wall or other vertical surface.

The cabinet further comprises end walls 14 and 15, a base or bottom wall 16, and a front panel 17. As shown, the bottom wall is formed integrally with the rear wall 12, and the end walls 14 and 15 are formed integrally with the front panel, although variations in the construction of the cabinet are contemplated.

The front panel 17 is provided in its center with a longitudinally extending narrow slot 18, which at each end merges into a notch 19 in the proximate end wall for the purpose of permitting the

insertion of a knife or other bladelike member behind the free flap of the outermost folded sheet for the purpose of initially withdrawing the same through the dispensing slot 18.

Inside of the front panel are located upper and lower bearing plates 20, each of which at its outer edge is provided with a forwardly extending flange 21. The bearing plates extend obliquely forwardly toward the dispensing slot, and the inner edges of the respective plates are rearwardly bent to each afford a V-shaped bearing member 22, the inner edge 23 of which is reversely turned to afford a lip 24, which arrangement provides a flared or throated outlet converging toward the dispensing slot 18. This arrangement also affords a general convergence toward the slot which has the effect of bowing forwardly the foremost sheets toward the slot and loosening and separating them from the main body of the stack in preparation for withdrawal, while the configuration of the bearing plates 20 is such as to afford contact with the center region of the foremost sheet only along the ridges of the bearing members 22 which reduces surface friction to a minimum and which combines with the loosening of the foremost sheets incident to their bowing forward to permit easy withdrawal of the foremost sheet from the slot.

The cabinet is further provided with inner plates or platform members 25 which stand in spaced relation to one another, and each of said members has its inner edge downturned to afford a flange 26 provided with a longitudinally extending guide slot 27, which slots are adapted to receive the ends of a pintle 28 carried by tongues 29 depending from a follower plate 30, the center portion of which is bent forwardly to afford a foot 31, which underlies the rearmost of the stack of interfolded sheets S and serves to prevent any of the sheets from becoming dislodged and slipping under the lower edge of the follower plate. The foot 31 lies flush with the surfaces of the platform members 25, so that the lower edges of the folded sheets comprising the stack are evenly supported across the base of the stack.

The upper edge 32 of the follower plate 30 is rearwardly flared to assist in the introduction of a stack of sheets, and the follower plate is provided on its rear face equidistantly from its vertical center with vertically extending flanges 33 provided with guide slots 34 for the reception of a pintle 35 carried at the forward end of a link plate 36, the rear end of which is pivoted on a

pintle 37 surrounded by a coil spring 38, the end 39 of which bears forwardly and upwardly against the link plate and serves to urge it forwardly during all positions of adjustment of the follower plate.

The follower plate may be retracted to the left hand position indicated in dotted lines in Fig. 2, in which position it may be retained by means of a finger 40, the upper end of which is offset at 10 41 and pivoted to a pin 42 extending through the rear wall of the cabinet near the upper edge thereof.

The length of the link plate in relation to the follower plate is such that when the follower plate 15 is completely retracted the pintle 35 on the link plate will engage the slots 34 near the lower ends thereof and thus apply feeding pressure near the base of the follower plate, which point of application is desirable at this stage in overcoming 20 the friction of the base of the entire stack of sheets which must be continuously fed forward as the withdrawal of successive sheets continues. However, as the stack becomes progressively reduced and depleted, the forward advancement of 25 the follower plate will progressively lift the point of application for the feeding pressure, so that ultimately the feeding pressure will be exerted above the center of the follower plate. This progressive variation in the point of application of 30 the pressure, commensurate with the reduction in the thickness of the stack, serves to hold the follower plate in substantially vertical relation during all stages of the feeding operation, so that the feeding will progress uniformly irrespec- 35 tive of the dimensions of the stack.

It will be understood that the stack S consists of folded and interleaved sheets of waxed paper whose free forward edges are alternately presented upwardly and downwardly in conformity 40 with well understood practice, and as the outermost sheet is withdrawn there will be a tendency to displace the adjacent sheets either upwardly or downwardly, as the case may be, which tendency toward downward displacement is prevented 45 by the contact of the base of the stack with the platform members 25, while a like tendency toward upward displacement is prevented by inwardly extending fingers 43 which are located in position to overlie the outermost folded sheets 50 which are subject to this displacing tendency.

In order to permit inspection of the interior of the cabinet, the side walls thereof are provided with slots 44 extending toward the forward edges thereof.

55 The above described arrangement of the follower plate and associated parts is peculiarly fitted to the feeding of stacked sheets of waxed paper which require careful guiding and manipulation and the proper application of feeding pressure in order to overcome the tendency toward lateral displacement in the stack due to the smooth and somewhat slippery character of the sheets which afford but slight frictional contact with one another.

60 Figs. 4 and 5 illustrate a modification of the feeding mechanism which in this instance includes a follower plate 45 which is carried and suspended at the forward end of a link plate 46 pivoted on a pintle 47 at the lower rear corner 70 of the cabinet and urged forwardly by a coil spring 48. The follower plate operates in conjunction with a backing plate 49 which is provided with a forwardly extending foot 50 which underlies and supports the rearmost sheets in the stack. The 75 upper edge 51 of the backing plate is bent for-

wardly to bear against the upper margin of the follower plate, and the side edges of the backing plate are provided with rearwardly turned flanges 52 for purposes of reinforcement.

The center of the follower plate is provided 5 with a cut-out or recess 53, the side edges being provided with flanges 54, which arrangement affords clearance for the swinging movements of the link plate 46 which rides upon a bead 55 formed across the base of the recess 53. In this 10 instance, as indicated in dotted lines, the folded sheets of the stack are supported and fed forward by the conjoint action of the follower plate and backing plate.

The follower plate is freely mounted upon the 15 free end of the link plate 46 but is held against rearward deflection by contact of the upper edge 51 of the backing plate, which plate will be held substantially vertical by the engagement of the foot 50 with the base of the stack. This modification, although it does not possess all of the advantages of the mechanism first described, may, nevertheless, be used with satisfactory results under ordinary circumstances.

Although the invention is primarily designed 25 to meet the special requirements involved in the even and uniform feeding of waxed paper wrapping sheets in interleaved relation to one another in a stack, nevertheless, the mechanism is well adapted to the feeding of sheets of ordinary un- 30 waxed paper, which may be used either as wrappers or as napkins, towels, toilet sheets or the like.

I claim:

1. A dispenser for folded sheets, comprising a container having a wall provided with an elongated slot for the withdrawal of the sheets, a follower plate bearing against the rear of the stack of sheets, a swinging link member pivoted at its rear end to the dispenser at a point vertically offset with respect to the center of the vertical axis 40 of the follower plate and on an axis parallel with the major axis of the slot, a member on the follower plate affording sliding engagement for the free end of the link member, spring means for urging the link member forward to advance the 45 follower plate and bow the sheets forwardly toward the slot, platform members above the base of the container and in spaced relation to one another to afford a center space and having the opposed edges of the platform members downturned to provide flanges having guide slots 50 therein, a member downwardly extending from the base of the follower plate into said center space and a pintle having its ends laterally projecting from said downwardly extending member 55 into said guide slots to afford a guide for the lower end of the follower plate.

2. A dispenser for folded sheets, comprising a container having a wall provided with an elongated slot for the withdrawal of the sheets, a follower plate bearing against the rear of the stack of sheets, a swinging link member pivoted at its rear end to the dispenser at a point vertically offset with respect to the center of the vertical axis of the follower plate and on an axis 65 parallel with the major axis of the slot, a member on the follower plate affording sliding engagement for the free end of the link member, spring means for urging the link member forward to advance the follower plate and bow the sheets forwardly toward the slot, platform members above the base of the container and in spaced relation to one another to afford a center space and having the opposed edges of the platform members downturned to provide flanges having 70 75

5 guide slots therein, a member downwardly extending from the base of the follower plate into said center space and a pintle having its ends laterally projecting from said downwardly extending member into said guide slots to afford a guide for the lower end of the follower plate, and a foot 10 on the lower edge of the follower plate being flush with the upper surfaces of the platform members and in position to underlie the lower edges 15 of the rearmost sheets.

10 3. A dispenser for folded sheets, comprising a container having a wall provided with an elongated slot for the withdrawal of the sheets, a follower plate bearing against the rear of the stack 15 of sheets, means for advancing the follower plate, supporting means for the lower edges of the sheets, said means having an opening formed therein and having guide members formed along the edges of said opening below the surface of 20 the supporting means, a member projecting downwardly from the lower edge of the follower plate and into said opening and having means engaging the guide members for guiding the lower edge of the follower plate from points below

the level of the supporting means for the sheets, and a foot on the lower edge of the follower plate being flush with the upper surfaces of the supporting means and in position to underlie the lower edges of the rearmost sheets. 5

4. A dispenser for folded sheets, comprising a container having a front wall provided with a dispensing slot extending medially thereof, said wall being provided on its inner side with obliquely disposed plates affording bearing surfaces on 10 opposite sides of the slot and disposed in generally convergent relation toward the edges of the slot, each of said plates at a point adjacent to the slot being reversely bent and then forwardly and obliquely bent to afford an inwardly extending ridge on each side of the slot and a threated entrance converging to the edges of the slot, said ridges in conjunction with the outermost surfaces of said plates affording reduced areas of contact for the foremost sheet of a stack and serving to 15 bow the stack outwardly in its center toward the slot, and means for applying feeding pressure to the rear of the stack to bow the same outwardly. 20
